JOHN O. SIMPSON, OF ILION, NEW YORK, ASSIGNOR TO REMINGTON ARMS AND AMMUNITION COMPANY, OF ILION, NEW YORK, A CORPORATION OF NEW YORK.

MAGAZINE-FIREARM

1,061,787.

Specification of Letters Patent. Patented May 13, 1913.
Application filed November 29, 1912. Serial No. 734,004.

To all whom it may concern:

Be it known that I, JOHN O. SIMPSON, a citizen of the United States, residing at Ilion, county of Herkimer, State of New York, have invented an Improvement in Magazine-Firearms, of which the following is a specification.

This invention is applicable to magazine firearms generally and has for its object to provide an attachment for the magazine that will reduce the number of possible shots to two. In other words the invention is a converter having for its object to convert any magazine firearm into a two-shot fire-arm and no more.

With this end in view the invention consists in the novel construction and combination of parts which will be hereinafter described and then specifically pointed out in the claims hereunto appended.

In the accompanying drawing forming a part of this specification, Figure 1 is a view of so much of a magazine firearm as is necessary to illustrate the construction, application and operation of my novel improvement, the barrel being in elevation, the receiver partly in elevation and partly in section, the magazine in section and one form of my novel improvement partly in elevation and partly in section, and Fig. 2 is a view partly in elevation and partly in section of a variant form of the improvement, detached.

10 denotes the barrel, 11 the receiver, 12 the magazine, 13 the magazine plug, 14 the magazine spring and 15 the follower, all of which may be of any ordinary or preferred construction. The magazine plug is secured to the outer end of the magazine. The follower is ordinarily a sheet metal thimble and is shown as having a closed end. The magazine spring bears against the magazine plug and the end of the follower and normally acts to hold the follower at the rear end of the magazine as shown in the drawing. The follower is provided with an enlarged forward end which engages an internal shoulder 16 on the magazine, to limit the inward movement of the follower, and also serves as a bearing upon the inner wall of the magazine.

My novel improvement comprises a member 17, which may be tubular as in Fig. 1 or

solid as in Fig. 2, a larger tubular member 18 within which member 17 may slide telescopically, a head 19 at the forward end of tubular member 18 and a spring 20 which bears against member 17 and the head. In the form illustrated in Fig. 1, member 17 is made tubular and its rear end is partly 55 or wholly closed as at 21, by turning the metal inward to form a bearing for the spring. In the form illustrated in Fig. 2, member 17 is made solid and the spring is shorter and bears against the forward end 65 of the member. The function of the spring is to retain member 17 in engagement with the follower. The rear end of tubular member 18 is provided with a stop 22, as a rolled or swaged bead, and the forward end of 70 member 17 is provided with an enlargement 27 which is adapted to engage the stop to limit the inward movement of member 17 and also to serve as a bearing upon the inner wall of tubular member 18. Head 19 75 is of just suitable size to pass within the magazine spring so that the converter is effectively centered in the magazine, and is provided with a hub 23 which passes within tubular member 18 to which it is secured 80 as by a rivet 24.

In use, the operator can insert a cartridge in the barrel and one cartridge but no more in the magazine. This for the reason that tubular member 18 is made long enough so 85 that should an attempt be made to insert a second cartridge in the magazine, the end of the follower, indicated by 25, will engage the rear end of tubular member 18, indicated by 26, and prevent the insertion of 90 an additional cartridge into the magazine. I thus strictly limit the capacity of the fire-arm to two cartridges by restricting the forward movement of the follower.

In assembling the converter, member 17 is 95 passed into tubular member 18 and forward until the shoulder on member 17 engages the stop on member 18. The spring is then inserted and hub 23 is inserted into member 18 and riveted in place, thus making the converter a self-contained unit.

To transform a magazine firearm into a two-shot fire-arm, the magazine plug is removed, leaving the magazine spring in place, the converter is inserted into the magazine, within the magazine spring, and the

magazine plug is returned to place, leaving the head of the converter abutting against the magazine plug.

Having thus described my invention I claim:

- 5 1. A magazine firearm converter for insertion within the magazine spring comprising a tubular member, a second member adapted to slide telescopically therein and 10 means for retaining said second member in an extended position.
- 15 2. A magazine firearm converter for insertion within the magazine spring comprising a tubular member, a second tubular member adapted to slide telescopically therein, a spring for holding said second member in an extended position and a head secured to the first member for retaining the spring in place.
- 20 3. A magazine firearm converter for insertion within the magazine spring comprising a tubular member, a second member adapted to slide telescopically therein, a spring for holding said second member in an 25 extended position, means for retaining said members in engagement and means for retaining the spring in place.
- 30 4. A magazine firearm converter for insertion within the magazine spring comprising a tubular member, having a stop at one end, a second member adapted to slide telescopically therein and having a shoulder adapted to engage the stop, for the purpose set forth, a spring for holding said second 35 member in an extended position and means for retaining the spring in place.
- 40 5. A magazine firearm converter for insertion within the magazine spring comprising a tubular member having a stop at one end, a second tubular member adapted to slide telescopically therein, said second member having a closing at one end and a

shoulder at the other end adapted to engage the stop, a spring engaging the end of the second member, for the purpose set forth, and a head secured to the first member against which the spring bears and which retains it in place.

6. In a firearm of the character described, the combination with a magazine, a magazine plug, a magazine spring and a follower, of a tubular member having a head secured thereto which lies within the magazine spring, a second tubular member adapted to slide telescopically in the first member and a 55 spring within the tubular members and engaging the second tubular member and the head, whereby said second member is held in engagement with the follower, substantially as described, for the purpose specified.

7. In a firearm of the character described, the combination with a magazine, a magazine plug, a magazine spring and a follower, of a tubular member, a second tubular member adapted to slide telescopically therein, and a spring within the tubular members adapted to retain the second member in engagement with the follower.

8. In a firearm of the character described, the combination with a magazine, a magazine plug, a magazine spring and a follower, of a tubular member having a stop, a second member adapted to slide telescopically in the first member and having means for engaging the stop and a spring acting to hold the second member in engagement with the follower.

In testimony whereof I affix my signature in presence of two witnesses.

JOHN O. SIMPSON.
